[57] CLAIM

The ornamental design of the table lamp, as shown and described.

DESCRIPTION

FIG. 1 is a front perspective view of a table lamp showing my new design;

FIG. 2 is a front elevational view thereof, the rear being a mirror image;

FIG. 3 is a side elevational view thereof, the opposite side being a mirror image;

FIG. 4 is a top plan view thereof; and,

FIG. 5 is a fragmentary exploded view of the lamp, showing the tubular lens separated from the top portion of the lamp for purposes of disclosure.

The lamp is fragmentarily shown in FIG. 5 for convenience of illustration.

FIG. 1

FIG. 2

FIG. 3

FIG. 4
